STAPLE FIBER CUTTER WITH MEANS TO VARY LENGTHS OF FIBERS

Lester V. Jorgensen, Decatur, Ala., assignor to The Chemstrand Corporation, Decatur, Ala., a corporation of Delaware

Filed May 8, 1957, Ser. No. 657,858

1 Claim. (Cl. 83—420)

This invention relates to a cutting device particularly adapted to cut staple fibers from yarns, tows or ropes of continuous filamentary material, such as of rayon or other artificial filaments, nylon and other synthetic filaments, such as those formed from linear condensation polyesters, acrylonitrile polymers, and the like. More particularly the invention is concerned with a cutting apparatus and assembly of the Beria type which is particularly adapted to produce directly staple fibers having a plurality of lengths.

Very often in the textile industry it is desirable, and in fact necessary in many instances, to blend staple fibers of varying lengths when making yarns and threads and the like. It has also been determined that textile fibers of similar or different character, that is, whether natural, artificial or synthetic or of only one class, blend better during processing, particularly on the woolen or worsted systems, and produce a yarn of improved uniformity if the fibers have a diversity of lengths. Of course the optimum extent and distribution of such diversity differs according to the type of yarn or fabric which is to be produced and the textile system which one contemplates employing therefor.

Various apparatus and processes have heretofore been proposed for producing fibers of varying lengths from a single fibrous material but in most all instances, the proposed apparatus and methods leave much to be desired. For example, various type staple fiber cutting means have been proposed but usually the same are not capable of operation at normal commercial speeds due to complexity and excessive wear of parts. Likewise such apparatus have not been readily adaptable to existing commercial equipment.

It is a primary object of the instant invention to provide an apparatus capable of producing staple fibers having a diversity of lengths. It is another object of the invention to provide an apparatus which is capable of producing varying length staple fibers from one bundle of filaments and which may be employed with existing equipment. It is still another object of the present invention to provide a novel apparatus which is capable of producing staple fiber products comprised of mixtures of fibers of varying lengths and in which the various fibers may vary in other characteristics, such as denier, stretch, shrinkage, tenacity, and the like. Other objects and advantages of the present invention will be apparent from the drawing and description thereof hereinafter.

In the drawing, which illustrates a preferred embodiment of the invention,

Figure 1 is an isometric view of a preferred embodiment of the variable length staple fiber cutting means of the instant invention;

Figure 2 is a side elevation view of the cam employed in the embodiment shown in Figure 1; and

Figure 3 is a diagrammatic plan view, partly in section, of a portion of the embodiment of Figure 1 showing the means for deflecting or changing the path of travel of the filamentary material.

2

In accordance with the present invention the filamentary material to be cut, such as a tow or other bundle of filamentary material, is fed through a path to a cutting means at a constant rate of speed and means are provided adjacent the path of the filamentary material for periodically and continuously varying the length of said path whereby varying lengths of filamentary material are periodically and continuously presented in cutting position in the cutting means. Specifically, the means for varying the length of the path of travel of the filamentary material is a reciprocating means operating preferably in the horizontal plane of said path, although, as will be seen from the description hereinafter, said reciprocating means may be positioned to operate in the vertical plane, diagonal plane, or like plane of the filamentary material path.

For a detailed description of the invention, reference should be had to the accompanying drawing, the various figures of which illustrate a preferred embodiment of the invention. A strand of filamentary material 2 is fed by means of feed rolls 3 and 4 to a cutting device 5. The filamentary material is fed to the cutting means from a suitable source of supply, such as directly from a synthetic or artificial filament spinning machine or from a creel and is wrapped about the feed rolls 3 and 4 one or more turns. The cutter 5 shown is of the Beria type comprising a rotatably mounted cutter disk 6 having an entrance channel 7 which communicates with the radial channel 8. By means of centrifugal force the filamentary material is thrown radially outwardly from channel 8 into the wall of the knife 9, which may be stationarily mounted. In the practice of the present invention, it is essential that a cutter capable of absorbing fiber at extremely rapid changes of rate of feed be employed. Normally, cutters using centrifugal force, air blast, or vacuum systems may be used. Rotary cutters of the Beria type are preferred, however.

Adjacent the path of travel of the filamentary material 2, there is positioned a suitable stand or support 10, comprising legs 11 mounted on which are longitudinal members or supports 12 and 13 and cross members or supports 14 and 15 attached to members 12 and 13. Positioned intermediate the cross members 14 and 15 and parallel thereto, is a third cross member 16 which is also fastened to members 12 and 13. Mounted on the cross member 16 is a bearing 17, there being a similar bearing 18 mounted on the cross member 14. The bearings 17 and 18 support the rotatable shaft 19 keyed to which is cam 20.

50 A variable speed device or transmission 21 is positioned adjacent the stand or support 10 which in turn is driven by a motor or like power supply (not shown). Any convenient power supply and variable speed transmission may be employed. The shaft 22 of the variable speed device 21 is joined to shaft 19 by means of the coupling 23. When employing the present invention, in order to insure uniform results, it is essential that the speed of the cutter 5 and the cam 20 be synchronized. In order to insure such synchronization it is generally 55 desirable that the same motor or like power supply be employed to drive both the cutter and cam. This can be accomplished by means of the variable speed transmission 21, since, as pointed out below, the cutter and cam will not usually be driven at the same r.p.m.

60 Mounted on the longitudinal members 12 and 13 are bearings 24 and 25 respectively having the shaft 26 slidably mounted therein. Bearings 24 and 25 are positioned so that the shaft 26 is adjacent cam 20. Adjustably mounted on shaft 26 is a bracket 27 having a downwardly extending portion 28 which in turn is positioned in the elongated opening 29 of the cross member or bracket 30 fastened to members 12 and 13. The down-

wardly extending portion 28 serves to prevent twisting of the shaft 26 when in operation. The bracket 27 supports the rotatable cam follower or roller 31 which is positioned in the groove 32 on the face of cam 20. A channel guide or deflector guide 33 is positioned on the end of shaft 26 in such a manner as to engage the filamentary material 2 on its way to the cutter 5. It should be understood that while a channel guide is shown in the embodiment of the drawing, any other suitable guide may be used which is designed to prevent the sideways movement of the filamentary material passing therethrough, such as a slot, U-shaped guide, and the like. The channel guide has the advantage of easy threading upon start-up.

Brackets 34 and 35 are mounted on the longitudinal member 12 on either side of bearing 24. Adjustably mounted on brackets 34 and 35 and extending outwardly therefrom toward the path of travel of the filamentary material are pigtail guides or eyelets 36 and 37 respectively. While any suitable guide may be employed in place of those shown, the pigtail guides or eyelets have the advantage of being easily and readily threaded upon start-up and in case of a break in the filamentary material. In this regard, in the case of breaks or other reasons for shut-down, automatic stopping devices may be employed with the instant apparatus, such as that shown and described in U.S. Patent No. 2,722,983.

While not shown for sake of simplicity, the cam 20 can be driven through the variable speed transmission or drive 21 by a separate motor or by the rotary cutter motor. As will be seen from the subsequent description of operation of the instant apparatus, however, it is essential that the cam be operated in synchronization with the cutter and accordingly, some attachment to the rotary cutter motor is desirable. Such an attachment would be within the skill of an ordinary mechanic.

The operation of the variable length staple fiber cutting assembly of the present invention is as follows: the cam 20 is rotated at a constant rate of speed which causes the shaft 26 and guide 33 to reciprocate in a horizontal plane coincident with the plane of the filamentary material 2 which is engaged by the guide 33. By constant rate is meant that the speed of the cam is always in the same ratio or relationship to the speed of the cutter. The shaft 26 is reciprocated by reason of the cam follower 31 riding in the groove 32 on the face of the cam. It will be noted (Figure 2) from the shape of the groove 32 that the guide 33 will be at a starting position coincident with the path of travel of the filamentary material and will be moved outwardly therefrom and returned to the starting position twice during one complete revolution of the cam 20. The effect of this motion of channel guide 33 is to lengthen the path of travel of the filamentary material between the feed rolls 3 and 4 and the cutter 5. This in turn causes a difference in the length 2A (Figure 1) of filamentary material presented in cutting position. The amount of deviation of the strand or filamentary material can be varied by changing the size of cam 20 and also by moving the stationary guides 36 and 37 toward and away from the reciprocating or channel guide 33. For efficient operation the channel guide 33 should be in neutral position, that is, coincident with the normal path of travel of the filamentary material 2 at the start-up of the apparatus and the knife blade 9 should be touching the filamentary material to be cut 2A.

To illustrate in more detail the operation of the apparatus, the following specific example is given. The rotary cutter 5 was set to operate at a speed of 4500 r.p.m. The speed of the godets or feed rollers 3 and 4 was adjusted to give cut fibers or a staple length of 3 inches when the cam 20 and the reciprocating channel guide 33 was not in operation. With this setting on the cutter and feed rolls and using a cam 20 approximately 20 inches in diameter and constructed as shown in Figure 2, staple

fibers varying in length from 1 inch to 5 inches were obtained. It is well to note here the shape of the groove 32 of cam 20 and in this regard reference should be had to Figure 2 of the drawing. The cam is divided into increments of 36° each and designated by the letters A to J. As the cam follower 31 goes through each of the increments A, B, D, E, F, G, I and J the channel guide 33 is moving. The increments C and H represent the dwell time of the cam and when the follower 31 passes there-through, the guide 33 is stationary at the end of the outward stroke. It will be noted that the groove 32 is so shaped as to cause the channel guide 33 to be moved outwardly and returned to its starting position, coincident with the filamentary material path, twice during a single revolution of the cam.

There are 10 increments (A-J) on the cam which means that 10 pieces of filamentary material will be cut during one revolution of the cam. This means the cam must rotate only once for each ten rotations of the cutter or at a speed of 450 r.p.m. since in this example, the cutter was operated at 4500 r.p.m.

As the cam 20 is rotated the channel guide 33 deflects the moving strand of filamentary material. In our example, the first increment on the cam (E) increased the strand 2 path by two inches. These two inches were subtractive from the basic feed of 3 inches per cut of the rotary cutter. The next increment (D) of the cam caused a further increase in the strand path of another inch before the next cut-off at the cutter. The third increment (C) of the cam is zero, which produced a dwell at the previous stage, which, it should be noted, does not affect the strand speed as it is merely displaced until the next cut-off. That is to say, during the increment C the filamentary material presented in cutting position will return to 3 inches since the strand speed remains constant. After passing through increment C the next two increments of the cam B and A are the reverse of E and D, and accordingly, as the cam follower passed therethrough, the strand path was decreased resulting in proportionately greater lengths of cut pieces of filamentary material, that is, greater in length than the normal 3 inch feed setting of the mechanism. These five increments of the cam constitute $\frac{1}{2}$ cycle and at the end thereof the channel guide is back to its neutral centerline of reference, the filamentary material path. The next half cycle of the cam is a repetition of the first.

It is well to note here the action of the present mechanism. The basic feed of the strand was 3 inches per revolution of the cutter. The first stage or increment E of the cam robbed the strand, or in reality, the cutter, of 2 inches, hence the cut was $3'' - 2''$ or $1''$. The second stage or increment D stole only one inch, hence the cut was $3'' - 1''$ or $2''$. The third stage or increment C stole nothing, so the cut was $3'' - 0''$ or $3''$. The fourth stage or increment B refunded the inch the increment D stole, hence the cut was $3'' + 1''$ or 4 inches. The fifth stage or increment A replaced the 2 inches stolen by increment E, so therefore the cut was $3'' + 2''$ or 5 inches. Therefore, in one-half of a cam cycle of five stages there was produced five lengths of fiber of $1''$, $2''$, $3''$, $4''$ and $5''$, or an aggregate of 15 inches of strand or filamentary material. The same cutting action was repeated during the second half cycle of the cam, thus processing 30 inches of the filamentary material per revolution of the cam. Since the cam was operated at 450 r.p.m. a total of 13,500 inches of filamentary material was cut every minute.

As previously pointed out, it is desirable for most efficient operation, to have the shafts of the cutter and cam interlocked to insure that both are driven at a constant speed without variation. Unless the cam and cutter shafts are interlocked, any slight speed error, for example, as in our above example, the speeds of cam and cutter were 449 r.p.m. and 4500 r.p.m. instead of the desired 450 r.p.m. and 4500 r.p.m., would result in a precessive 75 phase shift of cutter to cam or measuring device result-

ing in length variations between steps or increments. This phase shift can be eliminated by employing a suitable variable speed device, such as 21 in the drawing.

As pointed out hereinbefore, the guides 36 and 37 may be any desired distance apart depending on the amount of deflection of the strand path desired and the size of the cam 20 being employed in a particular cutting operation. For example, when the guides 36 and 37 are positioned 12 inches apart and the distance from each guide to the deflection point (guide 33) in 6 inches, it will require a deflection of 2½ inches from a straight line to increase the strand path by 2 inches in length, when employing a cam as shown approximately 20 inches in diameter. It will require a further deflection of 0.87 inch to increase the path one inch more. It should be noted that a slight decrease of the spacing of the guides 36 and 37 will reduce the length of the shortest fibers cut. On the other hand it should also be noted that a slight decrease in the feed roller speed will shorten the length of the longest fibers cut.

An important feature of the present invention is that it introduces rapid and controlled variations in the rate of feed of a strand or filamentary material to a cutting mechanism in such a way that the variations cancel out without disturbing the basic feed rate of the strand over an interval of time.

Another important feature of the instant device is that it enables one to produce a staple fiber product having any desired maximum and minimum fiber lengths and any desired length distribution may readily be obtained by varying the speed of the cam in relation to the cutter speed, by using different shaped cams, by varying the distance between the stationary guides, or by any combination of such alterations.

The filamentary material 2 proceeding to the godets or feed rollers 3 and 4 may be taken from a creel of wound packages of filamentary material, such as spools or bobbins of yarn or cakes of rayon. Alternatively, the filamentary material may be taken directly from a spinning machine, such as a machine for spinning artificial and synthetic filamentary material by extrusion of plastic material, such as viscose, acrylonitrile polymers, nylon, and the like, through the orifices of spinnerets from which it is drawn through a suitable coagulating medium about the periphery of a godet positively driven at substantially constant speed, or in succession about the periphery of a plurality of such godets between any two or more of which the material may, if desired, be subjected to stretching or shrinkage or to stretching and shrinkage in succession.

The present invention is advantageous in that it provides a simple means for continuously producing varied length staple fibers. Further, the present mechanism is

advantageous in that it can be employed with existing cutting equipment. Numerous other advantages of the invention will be apparent to those skilled in the art from a study of the instant description and drawing.

5 While preferred embodiments of the invention have been disclosed, the instant description is intended to be illustrative only, and it is to be understood that changes and variations may be made without departing from the spirit and scope of the invention as defined by the appended 10 claim.

I claim:

An apparatus for cutting filamentary material into fibers of predetermined various lengths, comprising a frame, a rotary cutter positioned adjacent to the frame for rotation 15 at a predetermined speed, means on the frame for guiding the yarn to the cutter, a movable guide adapted to engage the yarn adjacent to the guiding means for deflecting the path of the yarn to thereby vary the length of the yarn path so that the yarn is fed to the cutter at varying speeds, 20 a cam rotatably mounted on the frame and having a groove in the face thereof, means for driving the cam and the cutter in timed relationship so that the yarn is cut at uniform intervals during each revolution of the cam, a cam follower positioned in the groove in the cam, and 25 means interconnecting the cam follower and the movable guide for displacing said guide as the cam is rotated, said groove having a plurality of portions traversed sequentially by the cam follower, said yarn being cut as the cam follower passes the intersection of adjacent portions of said 30 groove, a first of said portions being arcuate and concentric with the axis of rotation of the cam for holding the movable guide stationary as said first portion is traversed by the cam follower, said groove having a pair of second portions connected to the first portion on opposite ends thereof and curving radially inward a predetermined radial distance, said groove also having a pair of third portions connected to the ends of the second portions and curving radially inward a radial distance substantially twice said 35 predetermined radial distance, said portions having a configuration such that the movable guide is displaced to vary the yarn path in such a manner that the yarn is cut into 40 lengths equal to successive multiples of a unit length.
